United States Patent Office.

A. D. GRAY, OF CHARITON, IOWA.

Letters Patent No. 98,252, dated December 28, 1869.

IMPROVEMENT IN COMBINED SEED-SOWER AND HARROW.

The Schedule referred to in these Letters Patent and making part of the same.

To all whom it may concern:

Be it known that I, A. D. GRAY, of Chariton, in the county of Lucas, and State of Iowa, have invented a new and useful Improvement in Combined Seed-Sower and Harrow; and I do hereby declare that the following is a full and exact description of the same, reference being had to the accompanying drawings, and to the letters of reference marked thereon.

This invention has for its object the production of an improved agricultural machine by means of which small seeds may be sown and covered at the same time; and to that end,

It consists in certain details of construction herein-after fully described, whereby the seed-sowing and covering devices are harmoniously united and operated in a single machine.

In the drawings—

Figure 1 represents a perspective view of my improved machine.

Figure 2, a sectional elevation through the line $x-x$, fig. 1.

Figure 3 represents views of parts detached.

To enable others skilled in the art to make and use my invention, I will now proceed to fully describe its operation and construction.

A represents the axle of the machine, supported by the wheels $a a$.

B represents the pole, which is united, at its rear end, to the axle A in any suitable manner.

Upon the axle A and pole B rests the main frame of the machine, which consists of the longitudinal beams C C, and transverse beams $c c$.

To the rear ends of the beam C C are attached, by hinges, the short beams D D, in which are provided bearings for the toothed roller E, as shown in the drawings.

F represents a bowed bar or rod, by means of which the beams D D are connected.

To this rod also is attached the rear end of the lever G, which latter has its fulcrum in the standard g , as shown.

To retain the lever in any desired position, the rack-bar H is provided, in any of the notches of which, the lever may be caught.

I represents the seed-hopper, which is provided with a perforated bottom, and also with a perforated slide, J, as shown in fig. 2.

This slide, at one end, extends outward beyond the hopper far enough to come into contact with the wheel K, located on the axle A, as shown.

The face of the wheel K is provided with triangular-shaped indentations, so that the slide J, by its contact with it, receives a regular reciprocating motion, its return movement being caused by the spring j, as shown in fig. 2.

For the purpose of removing the slide J from contact with the wheel K, when it is desired to cease the operation of sowing, I provide the lever L, which is attached to the slide by means of the slotted connecting-rod l and pin l.

To regulate the movement of the lever, I employ any suitable stop-device. A simple pin, as shown at x, will answer every purpose.

M represents a belt, which passes over the wheel K and e, by means of which a rapid motion is communicated to the roller E.

m m represent pulley-guides, by means of which the belt is kept in place.

For the purpose of preventing the wheels $a a$ from communicating motion to the seeding or covering-devices when the machine is backing or turning, I make them loose upon the axle, and provide them with suitable ratchet-devices, so that motion is communicated but in one way.

N represents the seat.

The operation of my machine is as follows:

The seed is placed in the hopper, from whence it is regularly delivered by the action of the reciprocating slide. As the seed falls to the ground, the earth is pulverized by the action of the toothed roller, and thrown upon it.

When it is desired to stop the delivery of the seed, the lever L is drawn aside far enough to relieve the slide J from contact with the wheel K. When it is desired to raise the roller E, the lever G is operated.

Having thus fully described my invention,

What I claim as new, and desire to secure by Letters Patent, is—

The machine described, consisting of the axle A with wheels $a a$; pole B, frame C C, $c c$, hinged beams D, toothed roller E, rod F, lifting-lever G, hopper I, spring-slide J, indented wheel K, adjusting-lever L, belt M, and guides m m, when combined as described, for the purpose set forth.

This specification signed and witnessed, this 18th day of October, 1869.

A. D. GRAY.
